Filed Jan. 26, 1970, Ser. No. 21,088

Term of patent 14 years

Int. Cl. D8—09

U.S. Cl. D8—179

FIG. 1

FIG. 2

FIG. 3

FIG. 4

FIG. 5

FIG. 6

FIG. 1 is a front elevational view of a decorative escutcheon for barrel locks, latches or the like, showing my new design in place on a conventional barrel lock.

FIG. 2 is a side elevational view of the escutcheon,
FIG. 3 is a top plan view thereof,

FIG. 4 is a front elevational view of a decorative escutcheon for barrel locks, latches or the like, showing a modified form in place on a conventional latch.

FIG. 5 is a side elevational view thereof, and

FIG. 6 is a top plan view thereof.

The conventional barrel lock and latch have been shown in broken lines merely to indicate environmental structure and they form no part of my invention.

I claim:

The ornamental design for a decorative escutcheon for barrel locks, latches or the like, as shown and described.
